UNITED STATES PATENT OFFICE.

ALLEN A. ARMSTRONG, OF CLEVELAND, OHIO, ASSIGNOR OF ONE-HALF TO PERRY W. FLICKER, OF CLEVELAND, OHIO.

EXERCISING APPARATUS.

1,409,992.

Specification of Letters Patent. Patented Mar. 21, 1922.

Application filed September 26, 1919. Serial No. 326,587.

To all whom it may concern:

Be it known that I, ALLEN A. ARMSTRONG, a citizen of the United States, residing at Cleveland, in the county of Cuyahoga and 5 State of Ohio, have invented certain new and useful Improvements in an Exercising Apparatus, of which the following is a specification.

The invention disclosed herein is an exercising device known to the trade as the Athleta Cycle, and is designed to provide an 10 improved cyclic exercising medium in which the operating parts are so constructed and arranged that the legs and the arms unite 15 in synchronized movements which require only the minimum expenditure of physical effort but yield the maximum value of healthful action to the entire body. The invention, therefore, is adapted to be advantageously used at all times and places where 20 physical exercise or development is sought or recommended as in gymnasiums, public schools, colleges, sanitaria, hospitals, hotels and other places, and especially in 25 the home for both adults and children, all substantially as shown and described and particularly pointed out in the claims.

In the accompanying drawings, Fig. 1 is a reduced side view of the apparatus and 30 Fig. 2 is an end elevation thereof. Fig. 3 is a plan view and section on line 3—3, Fig. 1, and Fig. 4 is a sectional view on line 4—4, Fig. 3, of the cross brace at the middle and bottom of the main frame.

Fig. 5 is an enlarged elevation of one of 35 the ball bearing coupling members for the hand crank, and Fig. 6 is a cross section thereof on line 6—6, Fig. 5. Fig. 7 is an enlarged side view of the upper end of the 40 post of one of the corner base brackets, showing the ball holder seated in the recess therein, and Fig. 8 is a sectional view thereof on the irregular line 8—8, Fig. 7.

Fig. 9 is an enlarged side view of one of 45 the corner brackets and posts with one foot crank and treadle and its coupling parts as assembled and united for operation, and Fig. 10 is a front elevation of Fig. 9 with the post partially sectioned. Fig. 11 is a sectional 50 elevation enlarged, of one of the removable ball bearings, comprising the holder plates, balls and a channeled collar, and Fig. 12 is a side elevation thereof. Fig. 13 is a cross section of one crank coupling for the connecting rods which unite the several cranks 55

together and showing the ball holder and bearing members clamped within the bottom seats therein.

Fig. 14 is an end view of one of the foot 60 pedals or shoes, and Fig. 15 is a sectional elevation of the adjustable rest plate and pivot support for said pedal. Fig. 16 is a vertical section of one of the crank couplings which support a rest plate and pedal, and Fig. 17 is a sectional view of one of the 65 recessed arms which are used to clamp the ball holder and bearing parts in the angular seat at the bottom of the rest plate and thereby connect the crank coupling in rotatable connection with the foot crank. Fig. 18 is 70 a sectional view lengthwise of the pedal plate shown in Fig. 14, and Fig. 19 is a similar view lengthwise of the adjustable pivot support shown in Fig. 15. Fig. 20 is a side view of the coiled spring used between the 75 pedal and its pivot support. Fig. 21 is a sectional view of the crank coupling, taken on line 21—21, Fig. 16, and Fig. 22 is a side view and section, of the clamping arm, on line 22—22, Fig. 17.

The invention as thus shown and 80 described comprises a main frame or structure in which there is a suitable base formed of wooden end and side pieces *b* seated within and connected by flanged brackets *d* having 85 inclined posts 2 extending upwardly in converging relation on each side piece *b*, and the top of these posts are tapped and connected by horizontal tie rods or tubes 3 and also by similar rods or tubes 4 at each side 90

which converge to a central point above the side pieces *b* and are tapped or threaded into a pair of diverging bosses in the bottom end of a common union or casting 5. This provides a rigid frame on opposite sides of the 95 base, especially when the extensions 6 at the top of castings 5 are connected by a cross brace 7. Side sway is also effectively prevented by a pair of inclined brace rods or tubes 8 extending upwardly on diverging 100 lines from the angular metal truss and cross brace 9 in the middle of the base and which brace rods screw into the unions 5 between the side tubes 4. Cross brace 9 is seated at its flanged ends upon the side pieces *b* and 105 secured thereto by a single tie rod 10 and similar tie rods 11 engage ears on the corner brackets and lock the wooden cross pieces *b'* within the flanged seats at the inside of said brackets *d*, so that the frame may be 110

easily assembled or disassembled for shipment at convenience.

The posts of corner brackets *d* and the unions *5* are each fashioned with an inside wall *12* having a lateral opening surrounded at four radial points by angular recesses *14*, see Figs. 7 and 8, within which a ball holder *15* is removably secured but fixed against rotation in an upright position opposite the lateral opening inside of a removable cone or cover *16*. Holder *15* comprises a pair of square plates riveted together side by side and of a size to fit the four corners within recesses *14* and flared outwardly about a central round opening in both plates to provide V-shaped ball races between the plates for a multiple number of balls *17*, and a sleeve or collar *18* having an annular ball bearing channel about its middle extends through and is adapted to rotate in the openings in said plates.

Each collar *18* is fastened upon the journal end of a crank arm *19*, and there are three crank members or shafts *20* and *21*, respectively, having such arms, one at each end of the base between the corner brackets *d*, and one between the unions *5*. The two crank members *20* are utilized as foot cranks, and the upper and centrally disposed crank member or shaft *21* provides a common hand crank for two persons standing opposite each other on the treadles or shoes *22* carried by the foot cranks. The straight ends of crank arms *19* are projected through the bearing collars *18* and fixed rigidly therein, so that rotation of the bearing collar is exclusively on balls *17* to insure noiseless and easy movements.

The middle connecting portion of each foot crank *20* is bent at an angle to the crank arms *19* and has straight portions on which the treadles *22* are mounted and which ends are rigidly but detachably clamped within the split extremities of the crank arms *19*. The hand crank *21* is also detachably clamped at its straight ends within the split extremities of the crank arms *19* which have rotatable bearing in unions *5*.

The treadles *22* are not directly engaged with the foot cranks but are pivoted at their bottom to upright lugs on a horizontal rest plate *23* which is mounted rigidly on a vertical stem *24* adjustably secured by a set screw *25* within a depending boss on a cast metal crank coupling *26* which is rotatably and detachably connected with the foot crank. Crank coupling *26* is in the form of a plate with a pair of angular recesses *27* in its bottom in each of which a ball holder *15* as hereinbefore described is adapted to be fixed against rotation, especially when clamped in place by a forked arm or bracket *28*. Holders *15* contain balls in bearing engagement with collars *18* which are fixed on the cranks *20*, and the arms *28* have angular seats for

the angular bottom corner of the plates of the holder so that when the arms *28* are detached from the bottom side of the coupling *26* the crank with its ball holders may be easily disconnected from said coupling. This is of advantage in assembling or disassembling the parts or in making renewals or repairs, or when substituting new ball holders for old ones, and in this connection it should be noted that the two pairs of crank couplings *26* for the two foot cranks are rigidly connected together by horizontal tie rods *29* which extend through depending eyes or ears *30* and are adjustably fastened by nuts *30'*, see Fig. 9. The two foot cranks are in this way coupled to rotate together, and the hand crank *21* is also coupled to the foot cranks to synchronize the movement of all three cranks. Thus the hand crank *21* is provided with ball bearing collars *18*, balls *17* and holders *15* which are removably confined within angular recesses in a round coupling member *33* made in two separable parts and having diverging bosses adapted to receive the upper screw-threaded ends of two converging connecting rods *31*, and the lower ends of these rods are united to the foot crank couplings *26* by nuts *32*, see Figs. 1, 2, 5 and 6.

Each treadle *22* has a strap *34* across its front to confine the foot and also depending perforated ears *35* at its rear pivotally engaged with a pin extending horizontally through the upright lugs on the rest plate *23*. A spiral spring *36* is seated in a socket at the front end of rest plate *23* to afford a yielding support for the treadle in front of the pivot pin, and the rear end *37* of said rest plate is projected upwardly to stop and limit the tilting or backward turning movement of the treadle. The rest plate *23*, spring *36* and treadle *22* may be raised together to different elevations above the foot crank and the coupling *26* to accommodate persons of different heights, but the radius of movement of the foot in describing a circle is not changed thereby. The spring is also connected at its ends to the rest plate and treadle, respectively, and acts both ways to control the tilting of the treadle, and the operator may lean forward or back and shift his weight by rocking on the pedals, thereby easing his position or accelerating or retarding the crank movement.

Having reference now to the hand crank *21* at the top of the structure it will be seen that there is a single gripping crank for the two opposite foot cranks. However, two revoluble hand grips *38* are provided end for end on each straight portion of the hand crank *21*, which correspond in position to the two treadles placed oppositely in line on the foot cranks below. In other particulars the hand cranks and the foot cranks are of substantially similar construction throughout

and have exactly the same stroke or radius of rotation and always cause one foot and hand on the same side to travel down together while the other foot and hand on the opposite side move up together in describing a circle.

I also employ a friction brake to control the speed of rotation of the connected cranks or to lock the same against rotation. Thus, in Fig. 1, I show the foot crank at the left as equipped with a brake wheel 40 at the outside of the stationary frame where said brake wheel is adapted to be engaged by a brake shoe 41 fixed at the lower end of a rod 42 which is mounted slidably in brackets 43 secured to the inclined pipe or tube 4. A pivoted cam lever 44 bears against the upper end of the brake rod 42 to effect a braking action on wheel 40, and a coil spring 45 is adapted to lift said rod and its brake shoe away from wheel 40 when the cam lever is thrown back. In this way the operator is enabled to control the starting and stopping movements of all three cranks and also retard the action in variable degree as he may elect.

What I claim is:

1. In an exercising apparatus, a foot crank and a hand crank and pedals on the foot crank adjustable to higher or lower levels relatively to the hand crank according to the reach of the operator, and link connections between said foot crank and hand crank to cause said parts to rotate together.
2. In an exercising apparatus, a pair of foot cranks and a hand crank, and operating connections between said cranks having corner coupling members engaged upon said cranks respectively, a rest plate having a

stem adjustably vertically within each coupling member of the said foot cranks, a pedal pivoted upon each rest plate directly above said stem, a spring beneath the front portion of each pedal and the rest plate and a limiting stop for each pedal at the heel thereof.

3. A stationary main frame, a pair of foot cranks and a single hand crank rotatably supported upon said frame, separate crank couplings rotatable on said foot cranks and transversely disposed detachable connecting rods uniting said couplings from pair to pair, pedal rests adjustable on said couplings and pedals pivotally mounted between their ends on said rests.

4. In an exercising apparatus, a knock-down structure comprising two separate foot cranks and a single hand-crank united to rotate in unison and a separable supporting frame for said cranks comprising separate base pieces, corner brackets adapted to connect said base pieces having posts, a central cross-brace connecting the sides of said base, transversely disposed tie rods binding said base pieces and brackets and cross brace together as a rigid unit, horizontal cross rods at right angles to said tie rods connecting said posts and vertically disposed inwardly inclined rods fixed in said posts and connected in pairs by unions at their top, and inclined braces connecting said unions with said central cross-brace, the whole constituting a rigid frame for the apparatus.

Signed at Cleveland, in the county of Cuyahoga, and State of Ohio, this 20th day of September, 1919.

ALLEN A. ARMSTRONG.
